(57) **CLAIM**

The ornamental design for a vessel with handle for sinus cavity rinse, as shown and described.

DESCRIPTION

FIG. 1 is a left, top, front isometric view of a vessel with handle for sinus cavity rinse.

FIG. 2 is a left elevation view of the vessel with handle for sinus cavity rinse of FIG. 1.

FIG. 3 is a right elevation view of the vessel with handle for sinus cavity rinse of FIG. 1.

FIG. 4 is a front elevation view of the vessel with handle for sinus cavity rinse of FIG. 1.

FIG. 5 is a rear elevation view of the vessel with handle for sinus cavity rinse of FIG. 1.

FIG. 6 is a top plan view of the vessel with handle for sinus cavity rinse of FIG. 1; and,

FIG. 7 is a bottom plan view of the vessel with handle for sinus cavity rinse of FIG. 1.

The broken lines shown in the drawings are for purposes of illustrating use and environment only and form no part of the claimed design.
